(57) **CLAIM**

The ornamental design for a wet saw roll cage, as shown and described.

DESCRIPTION

FIG. 1 is a bottom perspective view showing my new design;
FIG. 2 is a bottom plan view thereof;
FIG. 3 is a front elevational view thereof; and,
FIG. 4 is a side elevational view thereof.

The broken line showing of structural subject matter is included for the purpose of illustrating non-claimed subject matter and forms no part of the claimed design.
